UNITED STATES PATENT OFFICE

CLYDE HUDDINS, OF CAPTINA, WEST VIRGINIA, ASSIGNOR OF ONE-HALF TO LLOYD MEEKER, OF CAPTINA, WEST VIRGINIA

AMMUNITION CARRIER

Application filed March 4, 1930. Serial No. 433,045.

This invention relates broadly to ammunition carrying equipment for game hunters and others, and more specifically to a cartridge, or shell, carrier.

5 The primary object of the invention is to provide an improved form of magazine case for fire-arm cartridges or shells, adapted to be worn as a vestment and from which such cartridges may be conveniently removed as required.

10 A further object of the invention is to provide a body-harness equipment embodying cases in which a comparatively large number of cartridges may be carried without inconvenience to the wearer, in which cartridges are at all times disposed in a position or location permitting instant free access thereto, and in which the cartridges are securely retained against chance release thereof.

15 In describing the invention in detail, reference is herein had to the accompanying drawings, in which—

Figure 1 is a perspective view of the invention;

20 Figure 2 is an enlarged front elevation of a fragmentary portion of the upper end of one of the twin magazine cases;

Figure 3 is a similar view of the lower, or discharge, end of said case;

25 Figure 4 is a longitudinal section on line 4—4, Fig. 3;

Figure 5 is an enlarged section on line 5—5, Fig. 1; and—

30 Figure 6 is a view similar to Fig. 1, showing a modified form of the invention.

Referring to said drawings, 1 designates generally each of two magazine cases, 2 a body belt to which the lower end portions of said cases 1 are suitably attached, and 3 35 a neck-strap having its opposite ends permanently attached to said case, said strap being designed to be passed rearwardly over the shoulders and looped around the back of the neck of the wearer for supporting said cases.

40 Each of said cases comprises a strip of heavy waterproof fabric shaped to form a flat body 4 and two parallel tubes 5, the latter being disposed vertically in front of the plane 45 of said body 4 and being preferably formed

by turning the lateral edge portions of the strip into tubular form and attaching the same to said body by one or more vertical rows 6 of stitching, as shown. Said tubes 5, which constitute portions of separate magazines, or magazine-like receptacles, for fire-arm cartridges 7 terminate at a suitable distance above the lower end of the body 4 and each has attached to its lower end in aligned relation thereto the upper end of an open-sided metallic receptacle 8 of hollow cylindrical form having a bottom, or lower closed end 9. The cartridges 7 are received in each of said magazines in superposed stacked, or end-to-end, relation with the lowermost cartridge seated upon the bottom 9, and, as the lowermost cartridge is removed; or extracted, through the opening 10 provided therefor in the front side, or face, of said receptacle, the remaining cartridges freely gravitate until the lowermost thereof seats upon said bottom. Thus, the cartridges of each magazine may successively be removed through said opening until the supply has been exhausted.

45 As herein shown, the upper end of each receptacle 8 is made of tubular form and is received within the embrace of the lower end of the therewith-associated fabric tube 5, being held in such position by a metallic clamp 11 which is preferably of open-ring form. The lower ends of the receptacles 8 are suitably attached to the fabric body 4 and belt 2, as by rivets 12.

50 A pair of clamping fingers 13 formed integral with the cylindrical wall of the receptacle 8 project in a forwardly direction for partially embracing the lowermost cartridge at an appropriate midlength position for preventing chance dislodgment of said cartridge through the opening 10. Said opening possesses a depth at or adjacent to the position occupied by the upper end of the seated lowermost cartridge to permit said end to be grasped firmly between the fingers of the wearer, following which action the cartridge may be forcibly drawn outward through said opening, as shown in dotted lines in Fig. 4, the fingers 13 being sufficiently resilient that the requisite relative spreading thereof to effect release of the car-

tridge as the latter is drawn forward is readily permitted.

The upper end of each of the tubes 5 is suitably maintained in expanded cartridge-receiving condition, as by means of a metal ring 15 inserted within said end. As herein shown, the front upper edge portion of said ring 15 has an integral flange 16 disposed in depending substantially parallel relation to its body portion, said flange occupying seated clamping relation to a portion of the upper end of the tube, as shown in Fig. 2, and serving to retain the ring in place.

A flap 17 formed by an extension of the upper end of the body 4 is designed to be turned into closing relation to the upper ends of the twin tubes 5 formed on each fabric body 4, said flap being adapted to be secured in such closing relation, as by means of cooperative members 18 and 19 of a clasp, preferably of ordinary glove-clasp form, borne respectively by said flap and said body, as shown.

As is apparent, the magazine cases are designed to be supported in vertical positions in front of the shoulders of the wearer, the supporting neck-strap 3 being passed around the back of the neck. The belt 2 passed around the waist of the wearer and having the lower ends of said cases attached thereto serves to maintain the latter more or less stationary.

In the modified form of the invention shown in Fig. 6, two additional magazine cases 20, designed to occupy positions against the back of the wearer, are provided, the same having a construction identical with that of the cases 1 hereinbefore described, and having their lower ends attached to the body-belt. Two separate shoulder straps 21 are substituted for the neck strap, each being attached at its front end to one of the cases 1 and at the other end to the case 20 located at the corresponding side, as shown. A cross-strap 22 is preferably provided in a suitable location, as in a position for crossing horizontally the back of the wearer, for maintaining the relative vertical positions of the cases located on the right and left sides of the wearer.

What is claimed is—

1. In cartridge carrying equipment of the character described, a case comprising a fabric tube and a metal tube connected end to end in vertically aligned communicating relation, the metal tube being lowermost and having a closed lower end, said tubes being adapted to receive and maintain therein cartridges in stacked relation with the lowermost cartridge seated upon said closed end, said metal tube having an opening in its front wall through which the shells may successively be removed and having intermediate its ends coacting flexible fingers normally guarding said opening, and means whereby

said case may be supported on the body of the user.

2. In cartridge carrying equipment of the character described, a case comprising a fabric body having formed on the face thereof a plurality of magazine-like receptacles arranged in vertical parallel relation, each receptacle including an upper fabric tube and a lower metallic tube disposed in aligned communicating relation and adapted for receiving and maintaining therein in stacked relation a plurality of cartridges, said fabric tubes being formed by turning each of the lateral edge portions of said fabric body into tubular form and attaching the terminal edges thereof to said body, the metallic tube having a closed lower end and being adapted for having the lowermost cartridge rest thereon, said metallic tube having a longitudinally-extending opening in the front wall thereof through which the lowermost cartridge may be extracted and having coacting flexible fingers normally guarding said opening, and means for suspending said case from the shoulder of the user.

In testimony whereof, I affix my signature.

CLYDE HUDKINS.
